UNITED STATES PATENT OFFICE.

HENRY THOMPSON, OF TORONTO, CANADA.

BATHING-MACHINE.

SPECIFICATION forming part of Letters Patent No. 723,759, dated March 24, 1903.

Application filed June 27, 1902. Serial No. 113,489. (No model.)

To all whom it may concern:

Be it known that I, HENRY THOMPSON, a subject of the King of Great Britain, residing at Toronto, in the county of York, Province 5 of Ontario, Canada, have invented certain new and useful Improvements in Bathing-Machines, of which the following is a specification.

My invention relates to improvements in 10 bathing-machines; and the object of the invention is to provide a machine which shall obviate the necessity of bathers overexerting themselves by swimming and yet derive all the possible pleasure from immersion in comparatively 15 deep water and whereby children and those ignorant of the art of swimming may gain confidence and be taught without suffering any inconvenience; and it consists, essentially, of a circular platform resting on 20 a float or floats, a mast stepped in the center thereof, a gear and ring surrounding the mast and suspended from a cap surmounting the mast, a plurality of beams or poles projecting radially from the ring and supported by 25 suitable stays from the cap, a plurality of extension-rods designed to slide in and out on the aforesaid poles or beams, a body-strap suspended by rope or wire from the outer end of the extension-rods, a circularly-arranged series 30 of dressing-rooms inclosing an apartment in the center of the platform, ropes and pulleys designed to control the sliding of the rods, and suitable gear mechanism and motive power, the various parts being constructed 35 in detail as hereinafter more particularly described.

Figure 1 is a sectional perspective view of the machine. Fig. 2 is a perspective view of the rods, partly broken away. Fig. 3 is a view 40 of a portion of the mast, showing the means for pulling all the extension-rods to their inner position.

Like characters of reference indicate corresponding parts in each figure.

45 *a* is a circular platform, and *b* is a float supporting the same in the water. The float *b* may be made in any suitable form—that is, in the shape of an ordinary scow or several floats, as may be most desirable, to support 50 the weight thereabove.

c is a mast stepped in the center of the plat-

form *a* and having a pivotal point at the top thereof.

d is a cap surmounting the mast *c* and designed to turn on the pivotal point at the top 55 or on equivalent bearings.

e is a ring surrounding the mast and suspended from the cap *d* by the rods *f*, which are rigidly attached both to the ring and the cap in order that the turning of the ring may 60 also cause the cap to turn.

g is a gear surrounding the mast *c* and fixedly attached to the ring *e* or forming part thereof.

h is a gear meshing with the gear *g* and securely keyed to the top of the shaft *i*, which is rotated through the turning of the bevel-gear *j*. 65

k is a coacting bevel-gear which is turned by the revolving of the shaft *l*, which is operated by any suitable power. 70

m represents poles or beams projecting radially from the ring *e* and designed to be carried therewith in the rotation of the said ring.

n represents suspension-straps over the 75 poles *m* from the cap *d*.

o represents extension-rods, and *p* represents pulley-hangers fixedly attached to the inner ends of the rods *o* and designed to slide along the poles *m* by means of the rollers *q*. 80

r represents pulley-hangers firmly secured to the outer ends of the poles *m* and designed to allow the extension-rods *o* to slide therethrough between the rollers *s*.

t represents breast-straps swivelly hanging 85 from the ends of the ropes *u*, which depend from the springs *v*. The springs *v* are attached to the ends of the extension-rods *o*.

w represents pulleys supported from the hangers *r* and having double grooves. 90

x represents ropes attached to the outer ends of the extension-rods *o* and extending inwardly over the pulleys *w*.

y represents ropes attached to the inner ends of the extension-rods *o* and extending 95 outwardly over the pulleys *w*, so that a pull on any one end of the ropes *x* and *y* will alter the position of an extension-rod, as more fully explained hereinafter.

z represents ropes attached to the inner 100 ends of the extension-rods *o* and passing over suitable pulleys 2, hanging from the poles *m*,

are attached to the ring 3, surrounding the mast c.

4 represents hooks grappling the ring 3 diametrically opposite one to the other.

5 5 is a rope fixed to the shaft or drum 6, operated by the crank 7. The rope 5 spreads in the two ends 8 and 9, which are attached to the hooks 4.

It will be thus seen that the winding up of 10 the ropes 5 on the drum 6 will pull the ring 3 down the mast, simultaneously drawing in all the extension-rods o together to their inner position.

10 represents dressing - rooms in a circularly-arranged series surrounding the mast c and leaving the apartment 12 in the middle of the platform for the operating of the mechanism and storing of different articles.

11 represents the doors, which lead into the 20 various dressing-rooms, one of which shall serve as a passage to the middle apartment.

Having described the various parts involved in my invention, I shall now more clearly explain the utility thereof in the operation.

25 The machine constructed as explained in the foregoing is floated in a suitable bay, lagoon, or river and anchored by corner-posts or in any manner which shall be found most desirable to retain the machine in a fairly 30 steady position while in operation. The extension-rods are all in their inner position. Consequently the ring 3 is held down and preferably locked in that position until it is desired to use the machine. In this position

35 the outer ends of the beams m and rods o will be substantially flush, and the pulley-hangers p will be toward the inner ends of the poles m, while the pulley-hanger r will always remain in the same position. When desiring

40 to use the machine, the rope on the drum 6 is slackened and allowed to hang loose, so that the ring 3 may be pulled up the mast at the slightest jerk. The bathers after having disrobed in the dressing - rooms and donned

45 bathing-suits have the breast-straps buckled around them under the arms and around the chest, and this strap is then hooked onto the ropes u, and they are then dropped into the water, and by pulling the end of a rope y a

50 rod o is drawn out from its inner position, and at the same time a bather is sent several feet clear of the platform. This is done in every instance until all the extension-rods have bathers depending therefrom. The ma-

55 chine is then set in motion by starting the motive power, and through the gearing, as hereinbefore explained, the ring e is rotated around the mast, carrying with it in its rotation the radial poles m, and as these poles 60 support the rods o the bathers are carried around the platform while immersed for the most part in the water.

It must be understood that while I describe the particular construction for the slide of 65 the poles of the extension-rods by means of pulley-hangers other ways may be adopted—such as telescoping, rolling them out between

two parallel beams, and, in fact, many other constructions which would be equivalent to that illustrated and described herein.

The advantages of this machine are manifold for the bathers, as many desirous of bathing do not wish the exertion of swimming and yet want to be in the deep water where they can get a thorough immersion without touching the bottom, and, besides, the pleasure of slowly circulating around the platform cannot be overestimated, especially for children who are always desirous of this form of amusement.

The principle of the merry-go-round mechanism is practically adopted in my device for the operation thereof, and I do not desire to claim any novelty as regards the gearing or the general mechanism therein for the turning of the radial rods; but the remainder of the construction is, as far as I am aware, entirely novel.

What I claim as my invention is—

1. In a bathing-machine, the combination 90 with a float or floats having a circular platform resting thereon, of a mast stepped in the center thereof, a cap rotatably carried by the mast, a gear and ring surrounding the mast intermediate of its height, and suspended 95 from the cap by rigid rods, a pole or beam projecting from the ring beyond the edge of the platform and supported from the aforesaid cap, and suitable mechanism for rotating the ring around the mast, as and for the purpose specified.

2. In a bathing-machine, the combination 105 with a suitable float or floats having a circular platform resting thereon, of a mast stepped in the center thereof, a cap rotatably carried by the mast, a gear and ring surrounding the mast intermediate of its height, and suspended 110 from the cap by rigid rods, a plurality of poles or beams projecting radially from the ring and beyond the edge of the platform, a 115 depending rope from the outer end of each of the radial rods, and suitable mechanism designed to rotate the gear and ring around the mast, as and for the purpose specified.

3. In a bathing-machine, the combination 120 with a float or floats, having a circular platform resting thereon, of a mast stepped in the center thereof, a cap rotatably carried by the mast, a gear and ring surrounding the mast intermediate of its height rigidly suspended 125 from the cap, a plurality of poles or beams projecting radially from the ring and supported from the cap, a plurality of extension-rods designed to slide in and out on the poles or beams, a depending rope from the outer end thereof, and suitable mechanism for rotating the ring around the mast, as and for the purpose specified.

4. In a bathing-machine, the combination 130 with a float or floats having a circular platform resting thereon, of a mast stepped in the center thereof, a cap rotatably carried by said mast, a ring and gear surrounding the mast intermediate of its height and suspended by

rigid rods from the cap, a plurality or radial poles or beams projecting from the ring and supported from the cap, a plurality of extension-rods sliding in suitable hangers from the 5 poles or beams, a depending rope from the outer end of the extension-rods, having a breast-strap swivelly attached to the lower end of the extension-rods, and suitable mechanism for rotating the ring around the mast, 10 as and for the purpose specified.

5. In a bathing-machine, the combination with a float or floats having a circular platform resting thereon, of a mast stepped in the center thereof surmounted by a cap, a ring 15 and gear rigidly suspended from the cap intermediate of the height of the mast, a plurality of radial poles or beams projecting radially from the ring and supported from the cap, a plurality of extension-rods having a 20 limited sliding movement along the poles or beams, a suitable spring at the outer end of each extension-rod, a rope depending from each spring, a breast-strap swivelly attached to the depending rope, and suitable mechanism 25 for rotating the ring around the mast, as and for the purpose specified.

6. In a bathing-machine, the combination with a float or floats having a circular platform resting thereon, of a mast stepped in the 30 center thereof, a cap rotatably carried by said mast, a gear and ring surrounding the mast intermediate of its height and rigidly suspended from the cap, a plurality of poles or beams projecting radially from the ring and 35 supported from the cap, a plurality of extension-rods having a pulley-hanger fixedly attached at their inner end and sliding through the pulley-hanger fixedly attached to the outer ends of the poles or beams, a double-groove 40 pulley journaled in a lower extension by the pulley-hanger attached to the pole or beam, a rope attached to the inner end of the extension-rod and passing over a double-groove pulley and a rope attached to the outer end 45 of the extension-rod and passing over the double-groove pulley in the opposite direction, and suitable mechanism for rotating the ring around the mast, as and for the purpose specified.

50 7. In a bathing-machine, the combination with a float or floats having a circular platform resting thereon, and a mast stepped in the center thereof, a cap rotatably carried by said mast, and a ring and gear surrounding the mast intermediate of its height, and rigidly suspended from the cap, a plurality of extension rods or poles projecting radially from the ring and a train of gearing from motive power to the aforesaid gear, as and for 55 the purpose specified.

8. In a bathing-machine, the combination with a float or floats having a circular platform resting thereon, a mast stepped in the center thereof, a cap rotatably carried by said 60 mast, a gear and ring surrounding the mast intermediate of its height, rigidly suspended

from the cap, of a plurality of extension-rods projecting radially from the ring surrounding the mast beneath the aforesaid ring, a rope attached to each of the extension-rods, 70 and to the lower ring, and means for drawing the said lower ring downwardly on the mast, as and for the purpose specified.

9. In a device of the class described, in combination, a mast, a ring encircling the same, 75 a pole or beam projecting radially from the ring, an extension-rod designed to slide inwardly and outwardly and be supported by the pole or beam, a depending rope from the outer end of the extension-rod suitably arranged at its lower end, means for controlling the movement of the extension-rod, and a circular platform resting on suitable floats and designed to have the mast stepped in the center thereof, as and for the purpose specified. 80

10. In a device of the class described, a rope having a breast-strap swivelly attached to its lower end and at its upper end attached to a spiral spring, a radial rod designed to hold 90 the upper end of the spring, a circular platform resting on a float, a mast stepped in the center thereof, a ring intermediate of the height of the mast having a main rod projecting radially therefrom, means for staying the 95 said rod, and suitable mechanism for rotating the ring around the mast, as and for the purpose specified.

11. In a device of the class described, in combination, a circular platform resting on 100 a suitable float or floats, a mast stepped in the center thereof, a rotatable cap, a ring rigidly suspended from the cap and surrounding the mast intermediate of its height, a plurality of poles or beams projecting radially from the 105 ring, a plurality of slideable rods designed to lengthen the aforesaid poles or beams, a rope depending from the extreme outward end of the rod and having a supporting arrangement swivelly attached to its lower end, and suitable mechanism for rotating the ring around the mast, as and for the purpose specified. 110

12. In a device of the class described, a float, a horizontal extensible arm supported by said float at its inner end, and means carried by the float for causing the outer end of said arm to swing around the float, substantially as described. 115

13. In a device of the class described, a float, a mast carried thereby, an extensible 120 arm extending horizontally from said mast, means carried by the float for swinging said arm, and means also carried by the float for extending and retracting said arm, substantially as described. 125

Signed at Montreal, in the district of Montreal, in the Province of Quebec, Canada, this 31st day of May, 1902.

HENRY THOMPSON.
